ABSTRACT

A fluid system having a variable displacement fluid pump connected in a closed loop circuit to a fluid cylinder having a piston and a pair of connecting rods

extending from opposite sides of the piston externally of the fluid cylinder. A main directional control valve disposed in the closed circuit between the inlet and outlet of the fluid pump is adapted to selectively direct fluid to one side of the piston within the fluid cylinder, while exhausting fluid from the other side of the piston, to selectively move the piston within the fluid cylinder. The rate of movement of the piston in either direction of movement is controlled by the amount of fluid displaced by the fluid pump.

A second directional control valve is adapted to fluid FLUID from a second source of fluid to a pressure responsive displacement control mechanism to selectively vary the displacement of the fluid pump between a maximum and a minimum value. The rate of fluid flow to the pressure responsive displacement control mechanism is selectively varied to control the rate of displacement of the fluid pump and to thereby selectively control the rate of movement of the cylinder piston.

A remotely controlled pilot operated pressure relief valve, having an inlet connection in fluid communication with the outlet conduit of the fluid pump upstream from the main directional control valve and an outlet connection in fluid communication with the inlet conduit of the fluid pump between the fluid pump and the main directional control valve, is operable to reduce the normal operating pressure in the outlet conduit, and thus the operating pressure of the fluid in the main fluid cylinder, to a lower predetermined value when the pressure responsive displacement control mechanism is actuated to vary the displacement of the fluid pump toward a minimum value.

MULTIPLE PRESSURE FLUID SYSTEM

CROSS REFERENCE TO RELATED APPLICATIONS

The present application is a continuation-in-part of copending Patent Application Ser. No. 50,093, now U.S. Pat. No. 3,653,208 filed June 26, 1970 and entitled "Fluid System".

BACKGROUND OF THE INVENTION

1. Field of the Invention

The present invention relates to a fluid system for controlling the movement of a fluid motor and, in particular, the present invention relates to a closed loop hydrostatic system in which the output flow of a variable displacement pump is selectively directed at various rates to the opposite sides of a piston within a fluid cylinder and including means for selectively reducing the pressure of the fluid being communicated to one side of the fluid cylinder piston after a predetermined amount of movement thereof.

2. Description of the Prior Art

Heretofore, numerous fluid systems have been employed for controlling the rate of movement of a fluid motor and, particularly, such fluid systems have found extensive use in hydraulic machine tool drive transfer systems and the like. Such fluid systems are used to accelerate and decelerate a fluid cylinder respectively at the beginning and the end of its stroke prior to a feed movement. Such previously used fluid systems have normally consisted of a reservoir and a fluid pump for drawing fluid from the reservoir to supply the fluid cylinder and drive the same at some selected rate of movement. In all but the simplest of fluid circuits, the rate of movement of the fluid cylinder must be controlled and generally suitable valving means are employed between the pump and the fluid cylinder for this purpose. When a variable rate control of the fluid cylinder is desired, it is customary to employ either a meter-in, a meter-out, or a bleed-off system. Such systems generally include a deceleration valve connected in series with the pump and which is actuated by the movement of the fluid cylinder to variably restrict or stop the fluid flow between the outlet of the pump and the inlet of the fluid cylinder. When a finer rate control is desired, a feed control valve connected in parallel with the deceleration valve is utilized. The feed control valve, which may be of the meter-in or meter-out type, controls the rate of flow to or from the fluid cylinder and may either be a fine or coarse feed, depending on the desired application. If the feed control is of the meter-in type, the rate of fluid flow supplied to the fluid cylinder is controlled. If the fluid flow from the device is controlled, the circuit is known as a meter-out circuit. When a portion of the fluid supply is diverted to a reservoir, the circuit is known as a bleed-off circuit.

Thus, in the previously used systems, fluid flows directly from the pump through a deceleration valve, a feed control valve and to the fluid cylinder. In such systems, if the load greatly varies, the feed control valves require pressure compensation.

Such systems, although commonly used, are difficult to adjust and control and, because of the pressure compensation required for variable loads, they have a lower

efficiency than is desirable. Since acceleration and deceleration of the fluid cylinder are accomplished by means of a deceleration valve, such acceleration and deceleration are not smooth as the deceleration valves tend to generate pulsations in the fluid system which can damage the fluid cylinder and/or the fluid pump. Further, braking of the fluid cylinder is not possible as such fluid systems are not a closed loop system.

In numerous applications, such as the aforementioned transfer systems, the piston within the fluid cylinder is normally subjected to fluid which is maintained at a relatively constant high pressure during both the acceleration and the deceleration phases of a typical transfer cycle. Since the fluid cylinder transfer system must be properly aligned at the end of the deceleration cycle to effect the proper transfer of the workpieces or the like being carried, a positive stop is customarily employed to mechanically stop the fluid cylinder at a precise predetermined position, which is achieved by the fluid cylinder abutting the positive stop at the end of the deceleration phase. Since the pressure of the fluid driving the fluid cylinder is normally maintained at a constant high value, the fluid cylinder normally moves against the positive stop with a substantial force, resulting in a very noisy operation and possible damage to the positive stop which, in turn, might result in a shut down of the transfer system so as to effect a repair, all of which leads to higher production costs.

In addition, after the fluid cylinder abuts the positive stop in the previously used transfer systems, the high pressure acting against the piston in the fluid cylinder holds the fluid cylinder against the positive stop. In horizontal transfer systems, such a high holding pressure is generally unnecessary and thus results in an unneeded expenditure of input power with a corresponding reduction in the overall efficiency of the transfer system.

It would therefore be desirable to provide an improved fluid system which has all the advantages of previously used fluid systems without any of the aforementioned disadvantages while providing dynamic braking of the fluid cylinder.

SUMMARY OF THE INVENTION

The present invention, which will be described subsequently in greater detail, comprises a multiple pressure fluid system having a closed loop fluid circuit for selectively connecting the inlet and outlet of a fluid motor to the inlet and outlet of a fluid pump. The pump has separate feed means for varying its displacement between a minimum and maximum value so as to deliver fluid to the fluid motor such that the acceleration and deceleration of the fluid motor is controlled by varying the displacement of the fluid pump. Means are provided for selectively reducing the pressure of the fluid being directed to the fluid motor during deceleration, while providing dynamic braking.

It is therefore an object of the present invention to provide a multiple pressure fluid system for controlling the movement of a fluid motor which is easily adjustable and controlled more efficiently than previously used control circuits.

It is also an object of the present invention to provide a multiple pressure fluid system for controlling the rate of movement of a fluid motor in which the system pres-

sure during acceleration of the fluid motor is higher than the system pressure during deceleration of the fluid motor. The fluid system has a dynamic braking capability which in conjunction with the two pressure operation results in a smooth positioning of the fluid motor against a positive stop and a reduced power input for holding the fluid motor against the positive stop.

Other objects, advantages, and applications of the present invention will become apparent to those skilled in the art of fluid systems when the accompanying description of several examples of the best modes contemplated for practicing the invention is read in conjunction with the accompanying drawings.

BRIEF DESCRIPTION OF THE DRAWINGS

The description herein makes reference to the accompanying drawings in which like reference numerals refer to like parts throughout the several drawings and in which:

FIG. 1 is a schematic illustration of a fluid system of the present invention;

FIG. 2 is a fragmentary schematic illustration of a modification of the fluid system shown in FIG. 1; and

FIG. 3 is a fragmentary schematic illustration of another modification of the fluid system shown in FIG. 1.

DESCRIPTION OF THE PREFERRED EMBODIMENTS

Referring to the drawings and in particular to FIG. 1, there is illustrated a fluid system 10 comprising a control circuit 12 and a main circuit 14. The main circuit 14 comprises a variable displacement pump 16 connected in closed-loop manner by conduits 18, 20, 22 and 24 to a main fluid cylinder 26. Although a fluid cylinder is shown in the preferred embodiment, it is to be understood that other fluid motors may be used, such as but not limited to a rotary actuator or a hydraulic motor. Incorporated in the main circuit 14 is a conventional directional control valve 28 which is adapted to connect the conduits 18 and 20 selectively to the conduits 22 and 24 or to be positioned tandem-center so as to allow communication between conduits 18 and 20 but to prevent fluid communication between conduits 22 and 24.

The pump 16 may be of the well known axial piston type, comprising a housing 30 having a cylindrical barrel 32 rotatably mounted therein and suitably connected to a drive shaft 34. The cylinder barrel 32 is formed with a plurality of axial cylinder bores, each housing a piston reciprocal therein; only two of the bores and pistons being shown and respectively indicated by the numerals 36 and 38. Each piston 38 has a spherical outer end portion 40 carrying a bearing shoe 42 that engages a swash plate 44 which, in turn, is operatively coupled to a secondary fluid cylinder 46 by a connecting arm 48 for movement about a pivot 50 from a neutral, minimum displacement position 52 to a maximum or full flow position 54. A prime mover, such as an electric motor schematically illustrated at 56, is mechanically connected through a suitable coupling to the drive shaft 34 which, in turn, is supported within the pump housing by bearings 58 and 60.

As is conventional in pumps of the type illustrated, each cylinder bore 36 in the cylinder barrel 32 is provided with a cylinder port 62 adapted to alternately register with the inlet and outlet ports 64 and 66, respectively, as the cylinder barrel 32 rotates. The inlet and outlet ports 64 and 66 respectively communicate with the conduits 20 and 18.

The cylinder barrel 32, pistons 38, swash plate 44, and the input shaft 34 are immersed in fluid in a filled cavity normally referred to as a pump case 68. The pump 16 communicates with a reservoir 70 through a replenishing pump 92 and check valves 100 or 102 and a conduit 94 on inlet and a conduit 72 on drain, all of which will be described hereinafter.

The main fluid cylinder 26 has a cylindrical housing 74 with an internal bore 76 in which a cylindrical piston 78 is reciprocally mounted, dividing the internal bore 76 into two pressure chambers 80 and 82, respectively, on the opposite sides of the piston 78. The opposite sides of the piston 78 have cylinder rods 84 and 86 which extend through the opposite end walls and externally of the main fluid cylinder 26. The pressure chambers 80 and 82 of the cylinder 26 respectively have fluid ports 88 and 90 which, in turn, are respectively connected to the fluid conduits 24 and 22. Since the connecting rods 84 and 86 are of an equal diameter, the effective pressure responsive areas on the opposite sides of the piston 78 are also equal. The cylinder 26 operates in a well known manner to move the piston 78 in opposite directions within the cylinder bore 76 when one of the pressure chambers 80 or 82 is pressurized, while the other pressure chamber is exhausted.

The replenishing pump 92 is preferably of the positive fixed displacement type, such as a gear pump, and is also driven by the prime mover 56 through the drive shaft 34. The replenishing pump 92 is in communication with the reservoir 70 through a supply conduit 94 and a filter 96 for supplying the replenishing fluid to the main circuit 14 by means of a delivery conduit 98. The check valves 100 and 102 are spring biased and are in communication with the delivery conduit 98 and the closed loop main circuit conduits 18 and 20, respectively, for supplying replenishing fluid to whichever of the conduits 18 or 20 is the low pressure side of the closed main circuit through one of the check valves, while pressure on the high pressure side of the main circuit maintains the other check valve closed.

A spring biased relief valve 104 is provided for the replenishing pump 92 for relieving excessive fluid pressure in the replenishing delivery conduit 98 and for exhausting fluid to the reservoir 70 by means of a fluid conduit 106 connected to the pump case 68 and the conduit 72.

Similarly, a spring biased high pressure relief valve 105 is provided between the conduits 18 and 20 for relieving excessive fluid pressure from the conduit 20 during dynamic braking of the fluid motor 26 and is adapted to exhaust the fluid from the conduit 20 into the conduit 18 by means of a fluid conduit 107. In the embodiment illustrated in FIG. 1, the conduit 18 connected to the outlet 66 of the pump 16 is normally a high pressure conduit, while the conduit 20 connected to the pump inlet 64 is the low pressure conduit while the piston 78 is being accelerated. When the piston 78 is being dynamically braked, the pressure in the con-

duit 18 will be substantially higher than the pressure in the conduit 20. During the dynamic braking of the piston 78, the pump 16 will function as a motor in the conventional manner.

A pilot operated pressure relief valve 109 having its inlet connected to the high pressure conduit 18 and its outlet connected to the low pressure conduit 20 is normally set to discharge the fluid from the high pressure conduit 18 to the low pressure conduit 20 when the pressure in the conduit 18 exceeds a predetermined value which is the highest operating pressure at which the system is designed to operate, as for example 5,000 psi. The relief valve 109 may be connected to a pilot valve 113 by conduit 115 and a conventional directional control valve 117. When the relief valve 109 is connected to the pilot valve 113, the relief valve 108 functions to relieve pressure from the high pressure conduit 18 whenever the pressure therein exceeds a value, as set by the pilot valve 113, which is less than the design operating pressure, as for example 1,500 psi. Operation of the relief valve 109 at the lower value is prevented when the control valve 117 is positioned by switching means 168 in such a manner as to prevent communication between the valve 109 and the pilot valve 113. The manner in which the control valve 117 is actuated so as to communicate the pilot valve 113 with the relief valve 109 and the purpose for reducing the pressure in the high pressure conduit 18 will be described in greater detail hereinafter.

A modification of the two pressure system is illustrated in FIG. 2 and is particularly adapted for use in low flow transmissions (0-5 gpm flow). Low pressure operation is obtained in conduit 18 by replacing the pilot operated relief valve 109 and the pilot valve 113 with a conventional high pressure valve 300 for high pressure operation and a second low pressure relief valve 302 for low pressure operation. A solenoid operated selector valve 304 is disposed between the conduit 18 and the low pressure relief valve 302 and normally prevents communication therebetween. When low pressure operation is desired, the selector valve 304 is actuated to communicate the low pressure relief valve 302 to the conduit 18 and the system will function in the same manner as described with respect to the embodiment disclosed in FIG. 1. The discharge from both the high and low pressure relief valve 300 and 302 is to the conduit 20.

Referring again to FIG. 1, downstream of the directional control valve 28, the conduits 22 and 24 are respectively connected to the inlets of high pressure cross port relief valves 108 and 110 which at a predetermined pressure, eg: 5,000 psi, will exhaust the fluid pressure from one of the conduits to the other conduit in the same manner as the high pressure relief valve 109, so as to prevent damage to the main circuit in the event of over pressurization. It can thus be seen that the system is operable between high and low predetermined pressures while having dynamic capabilities.

Referring to the control circuit 12 for a description of the method of controlling the displacement of the fluid pump 16, there is illustrated a directional control valve 112 adapted to selectively connect fluid from the replenishing pump 92 to either of a pair of feed control valves 114 and 116 by conduits 118 and 120 respec-

tively. The feed valves 114 and 116 are respectively connected to the ports 122 and 124 of the secondary fluid cylinder 46 by means of conduits 126 and 128, respectively. The fluid cylinder 46 is similar in construction to the main cylinder 26 and comprises a tubular housing 130 having an interior bore 132 divided into two pressure chambers 134 and 136 by means of a reciprocally mounted piston 138, which, in turn, carries a connecting rod 140. Connecting rod 140 extends externally of the housing 130 and is operatively coupled at 142 to the swash plate connecting arm 48 of pump 16. The pressure chambers 134 and 136 are respectively connected to the conduits 126 and 128.

The feed control valves 114 and 116 may be of the conventional type and have restricted passages 144 and 146 which are adjustable such that each of the feed control valves may be pre-set to vary the flow rate therethrough over a wide range. Each of the feed control valves 114 and 116 includes a check valve 148 and 150, respectively, which permits fluid to bypass the restricted passages 144 and 146 in one direction. Thus, when the directional control valve 112 is in the position indicated, fluid flow is directed from the fixed displacement pump 92 through the conduit 120 to the feed control valve 116, bypassing the restricted passage 146 while flowing through check valve 150 and is then directed to the pressure chamber 136 on one side of the cylinder piston 140 to move the same leftwardly within the cylinder bore 132 to displace the fluid pump 16 toward its full flow position 54. Fluid on the opposite side of the piston cylinder 138 within the pressure chamber 134 will be exhausted through the cylinder port 122 and directed through conduit 126 to the feed control valve 114 at a rate of flow which is determined by the setting of the restricted passage 144. Fluid returns to the reservoir 70 through the directional control valve 112 and a conduit 152. When the directional control valve 112 is reversed so as to direct fluid flow through the check valve 148 of the feed control valve 114 to the pressure chamber 134 to move the piston 138 rightwardly, fluid is exhausted through the restricted passage 146 of the feed control valve 116 which, in turn, controls the rate of movement of the piston 138. As the piston 138 moves rightwardly, the swash plate connecting arm 48 is moved to the minimum displacement position 52.

The type of feed control illustrated is known as a meter-out control, that is, the rate of movement of the piston 138 within the secondary fluid cylinder 46 is determined by the rate of the fluid being exhausted from the pressure chamber 134 or 136, which, in turn, is controlled by the feed control valves 114 and 116. A detailed description of the feed control valves 114 and 116 is not necessary as such feed control valves are well known and commercially available.

It can thus be seen that the rate of change in the displacement of the fluid pump 16 is controlled by the feed control valves 114 and 116, so that, if the restricted passages 144 and 146 of the feed control valves are set to permit a high rate of flow to pass therethrough, the cylinder piston 138 will be displaced rapidly, causing a rapid change in the displacement of the fluid pump 16 which, in turn, when communicated to the main fluid cylinder 26 will generate a rapid acceleration and/or deceleration of the cylinder piston 78 therein.

The cylinder rod 140 carries a stop member 154 which is adapted to abut axially adjustable limit stops 156 and 158 so as to permit a variation in the displacement of the fluid pump 16 at predetermined intermediate displacements respectively below the maximum displacement of the fluid pump 16 and above the minimum displacement of the pump 16. The maximum displacement of the pump 16 occurs when the swash plate 44 abuts the wall 160 of the pump housing, while the minimum displacement of the pump 16 occurs when the swash plate 44 is disposed in a plane which is perpendicular to the longitudinal axis of the drive shaft 34.

In operation, when it is desired to direct fluid from the fluid pump 10 through the conduit 18, the directional control valve 28 and the conduit 24 so as to accelerate the piston 78 in the main cylinder 26 forwardly (to the right as viewed in the drawing) at a rapid rate, the directional control valve 112 of the control circuit 12 is actuated by a switching means 162 so as to direct fluid from the fixed pump 92 into the pressure chamber 136 of the fluid cylinder 46 to drive the piston therein leftwardly as viewed in FIG. 1 so as to stroke the swash plate 44 of the fluid pump 16 to the maximum displacement 54 or some other intermediate displacement as determined by the setting of the adjustable stop 156. Fluid from the secondary cylinder 46 is exhausted through the adjustable restricted passage 144 of the feed control valve 114 which is set to permit a high rate of fluid flow therethrough, thus permitting a rapid stroking of the pump 16 which, in turn, will displace a maximum amount of fluid into the conduit 18. The directional control valves 112 and 28 in the control and main circuits, respectively, are simultaneously actuated so that as the secondary cylinder 46 is actuated, fluid from the variable displacement pump 16 will be directed to the main fluid cylinder 26 to accelerate the piston 78 therein rapidly to the right as viewed in the drawing. After the piston is displaced at a rapid rate of acceleration and strikes a limit switch L1, the directional control valve 112 in the control circuit 12 is actuated by the switching means 162, so as to direct fluid to the pressure chamber 134 on the opposite side of the piston 138 in the secondary fluid cylinder 46. Fluid entering the secondary cylinder 46 will move the piston 138 rightwardly to stroke swash plate 44 toward the zero flow position 52 or some intermediate displacement as determined by the adjustable stop 158. The fluid in the pressure chamber 136 of cylinder 46 will be exhausted through the feed control valve restricted passage 146 at some predetermined rate which will control the rate at which the piston 138 of the fluid cylinder 46 strokes the pump 16 back towards a lower displacement.

Simultaneously with the actuation of the directional control valve 112 by the switching means 162, the limit switch L1 energizes the switching means 168 to position the directional control valve 117 such that the relief valve 109 is connected to the pilot valve 113. During this phase of the operation of the system, the fluid cylinder piston 78 is being dynamically braked which will cause the pressure in the conduits 20 and 22 to be substantially increased, while the pressure in conduits 18 and 24 is substantially decreased, putting the pump 16 in a "motoring" mode as hereinbefore mentioned. The dynamic braking relief valve 105 is functional to

relieve excessive pressure in the conduit 20 during this phase of operation. After the piston has been dynamically braked and a higher pressure is required in conduits 18 and 24 to move the piston rightwardly (as viewed in FIG. 1), as for example to overcome the static friction of the load to be moved, the pilot relief valve 113 is effective to maintain the system pressure at the aforementioned reduced predetermined value. The pressure within the outlet conduit 18 will cause the pilot 113 to open, thereby causing the relief valve 109 to direct fluid from the outlet pressure conduit 18 to the low pressure conduit 20, to maintain the pressure in the system at a substantially lower value as, for example, if the normal operating pressure used to accelerate the piston 78 within the fluid cylinder is pre-set at 5,000 psi then an appropriate value setting for the pilot relief valve 113 would be 1,500 psi. When the relief valve 109 is operable to reduce the operating pressure in the outlet conduit 18, the pressure acting against the piston 78 will be 1,500 psi. As the pump 16 is stroked toward a lower displacement, the rate at which fluid is directed to the main cylinder 26 is decreased, thereby decelerating the movement of the piston 78 within the main fluid cylinder 26. When the pump 16 is stroked to a minimum, the forward movement of the piston 78 of the main cylinder 26 will be brought to a minimum creep speed to seek a final stop position. A positive stop 166 is provided to insure that the cylinder piston 78 stops at a desired position.

The decreased displacement of the pump 16, combined with the reduced operating pressure acting to move the piston 78, provide a smooth positive positioning of the end of the connecting rod 86 against the positive stop 166. If desired, the actuating rod 86 may engage a limit switch L2 which functions to center the directional control valve 28 to a position wherein the conduits 22 and 24 are not in communication with the conduits 18 and 20 which, in turn, are now set in the closed loop arrangement as described hereinbefore. As an alternative, the limit switch L2 may be eliminated and the pump 16 displaced to a minimum position wherein it provides sufficient pressure, say 1,500 psi, to generate a holding force acting against the piston 78 to hold the end of the actuating rod 86 against the positive stop 166. The holding pressure cannot exceed the value determined by the pilot valve 113 as the same is still communicating with the conduit 18 via control valve 117.

Acceleration and deceleration of the piston 78 within the main cylinder 26 in an opposite direction away from the stop 166 (to the left as viewed in FIG. 1 of the drawings) may be achieved by reversing the flow from the conduits 18 and 20 to the conduits 22 and 24 by means of the directional control valve 28 without requiring any change in the setting of the feed control valves 114 and 116 as the volume of fluid required to move the piston in either direction at some predetermined rate is equal. Actuation of the directional control valve 28 to drive the piston 78 away from the position stop 166 toward its initial starting position is accompanied by a simultaneous actuation of the directional control valve 117 to prevent communication between the pilot valve 113 and the relief valve 109. As soon as communication between the relief valve 109 and the pilot valve 113 is closed, the pressure

in the high pressure conduit 18 will return to a higher value, say 5,000 psi, as determined by the load and limited by the high pressure relief valve 109.

Moving the directional control valve 28 to a tandem center or no flow condition will prevent fluid flow either to or from the cylinder chambers 80 and 82, quickly stopping the piston 78. Such a quick stop may be utilized in the event of an emergency when it is necessary to prevent damage to the machine tool or transfer mechanism which the connecting rod 86 and/or 84 is driving.

It can thus be seen that by proper utilization of the directional control valves 28, 112 and 117, the feed control valves 114 and 116, and the pilot operated relief valve 109, the piston 78 within the main cylinder 26 may be accelerated by a fluid at a first high pressure, while the piston is decelerated by a fluid at a second substantially lower pressure to provide dynamic braking and smooth positive positioning against a positive stop, and thus eliminating the aforementioned loud noise problem customarily encountered in prior transfer systems. At the same time, a lower pressure is provided for holding the fluid cylinder connecting rod against a positive stop, thus reducing the input power required with a resulting increase in the overall efficiency of the system.

Referring now to FIG. 3, another example of the present invention is illustrated in the form of a multiple pressure fluid system 200 comprising the control circuit 12 (not shown) and a modified main circuit 14A; and in which the components of the fluid system 200 illustrated in FIG. 2 have the same numeral designations as similar components of the fluid system 10 illustrated in FIG. 1. The control circuit 12 is not illustrated in FIG. 3 as it is identical to and operates the same as the control circuit 12 illustrated in FIG. 1. The pilot operated pressure relief valve 109, the directional control valve 117, the pilot valve 113, their associated conduits and the actuating means 168 have been eliminated from the main circuit 14A of the system 200 and replaced by a conventional high pressure relief valve 201 with its inlet port connected to the conduit 18 and its discharge port connected to the conduit 20, while the high pressure relief valves 108 and 110 have been replaced by a pair of remote control pilot operated pressure relief valves 202 and 204 located in the system downstream from the main directional control valve 28. The pilot operated pressure relief valve 202 has an inlet connection communicating with conduit 22 through a conduit 206 and an outlet connection in communication with the conduit 24 through a conduit 208, while the pilot operated pressure relief valve 204 has an outlet connection in communication with the conduit 24 through the conduit 208 and an inlet connection in communication with the conduit 22 through the conduit 206.

The relief valves 202 and 204 are adapted to be selectively connected to a pilot valve by means of a directional control valve 212, which in turn is selectively actuated by switching means 214.

The pilot valve 210 is adapted to open whichever one of the relief valves 202 or 204 that is in communication therewith through the control valve 212 so as to lower the pressure in the conduits 22 or 24 to a value which is substantially lower than the normal high operating

pressure, which pressure is a function of the load. When the piston 78 is being shifted rightwardly, as viewed in FIG. 3, the conduit 24 is the high pressure conduit, while the conduit 22 is the high pressure conduit when the piston 78 is being moved leftwardly as in FIG. 3.

During operation, when the piston 78 is being accelerated toward the positive stop 166 and the directional control valve 112 is actuated by the switching means 162 to decelerate the piston 78 as hereinbefore described, the control valve 212 is simultaneously actuated by the switching means 214 to connect the pilot valve 210 with the relief valve 204. After dynamic braking has occurred, the high pressure fluid in the conduit 24 is directed to the lower pressure conduit 22 and thus obtaining a reduction of the pressure in the system 200 from its normal high operating value to a substantially lower value in the same manner as hereinbefore described with respect to the circuit 10.

In the same manner, when the system 200 is operable to direct high pressure fluid to the conduit 22 to drive the piston 78 leftwardly, as viewed in FIG. 3, toward its initial starting position, and the deceleration thereof is required, the directional valve 112 is actuated by the switching means 162 to cause a decrease in the displacement of the fluid pump 16. Simultaneously, the switching means 214 actuates the control valve 212 so as to connect the pilot valve 210 to the relief valve 202, and after dynamic braking has been effected the pressure in the high pressure conduit 22 will be reduced to a substantially lower value in the same manner as described hereinbefore.

The multiple pressure fluid systems of the present invention have been found to be especially suitable for inline shuttle, lift and transfer systems wherein rapid movement, dynamic braking, combined with smooth acceleration and deceleration, and positive braking are important.

It can thus be seen that a new and improved closed loop multiple pressure fluid system has been provided which is much simpler in its construction than previously used systems, and which is more reliable, rapid and of low noise operation.

While the form of the embodiments of the present invention, as disclosed herein, constitute preferred forms, it is to be understood that other forms might be adopted all coming within the spirit of the invention and the scope of the appended claims which follow.

What is claimed is as follows:

1. A multiple pressure fluid system comprising: a fluid pump having a high pressure fluid outlet and a low pressure fluid inlet; a fluid motor having an output means responsive to fluid pressure for generating a movable mechanical output; first motor port means adapted to communicate fluid pressure to said output means to move said mechanical output in one direction, and second motor port means adapted to communicate fluid pressure to said output means to move said mechanical output in an opposite direction; a first conduit means connecting said pump high pressure outlet to one of said motor port means for communicating fluid pressure thereto;

a second conduit means connecting said pump low pressure inlet to the other of said motor port means for exhausting fluid pressure therefrom, such that said pump and motor are connected in a closed loop fashion;

controlled means connected to said first conduit means and operable upon actuation while said fluid pressure is being delivered from said pump to said motor for reducing the pressure in said first conduit means to a lower predetermined value;

means for actuating said controlled means in response to said fluid motor mechanical output after same has moved a predetermined distance in a selected direction, said pump continuing to deliver fluid pressure at said predetermined value after said controlled means is actuated; and

a valve means, said first and second conduit means comprising a first fluid line and a second fluid line respectively communicating said pump high pressure outlet and low pressure inlet to said valve means, and a third fluid line and a fourth fluid line respectively communicating said first and second motor port means to said valve means, said valve means selectively connecting said first and second fluid lines to said third and fourth fluid lines such that the high pressure fluid in said first fluid line is directed selectively to one of said third or fourth fluid lines to move said output member in opposite directions, while fluid in the other said third or fourth fluid line is exhausted through said second fluid line;

and pilot valve means selectively operable to control the pressure at which said relief valve opens, whereby the pressure in said first fluid line carrying said high pressure fluid may be selectively reduced to said lower predetermined value after said mechanical output is moved a predetermined distance.

2. A multiple pressure fluid system comprising:

a fluid pump having a high pressure fluid outlet and a low pressure fluid inlet;

a fluid motor having an output means responsive to fluid pressure for generating a movable mechanical output;

first motor port means adapted to communicate fluid pressure to said output means to move said mechanical output in one direction, and second motor port means adapted to communicate fluid pressure to said output means to move said mechanical output in an opposite direction;

a first conduit means connecting said pump high pressure outlet to one of said motor port means for communicating fluid pressure thereto;

a second conduit means connecting said pump low pressure inlet to the other of said motor port means for exhausting fluid pressure therefrom, such that said pump and motor are connected in a closed loop fashion;

a valve means, said first and second conduit means comprising a first fluid line and a second fluid line respectively communicating said pump high pressure outlet and low pressure inlet to said valve

means, and a third fluid line and a fourth fluid line respectively communicating said first and second motor port means to said valve means, said valve means selectively connecting said first and second fluid lines to said third and fourth fluid lines such that the high pressure fluid in said first fluid line is directed selectively to one of said third or fourth fluid lines to move said output member in opposite directions, while fluid in the other said third or fourth fluid line is exhausted through said second fluid line;

a first pressure relief valve having its inlet connected to said third fluid line and its outlet connected to said fourth fluid line;

a second pressure relief valve having its inlet connected to said fourth fluid line and its outlet connected to said third fluid line;

and pilot valve means selectively operable in response to a predetermined movement of said fluid motor output to control the pressure at which said first and second relief valves open, whereby the pressure in whichever of said fluid lines carrying said high pressure fluid may be selectively reduced to a lower predetermined value.

3. A multiple pressure fluid system comprising:

a variable displacement fluid pump having high pressure fluid outlet and a low pressure fluid inlet;

a fluid motor having an output member movable in response to fluid pressure;

first motor port means adapted to communicate fluid pressure to said output member to move said output member in one direction, and second motor port means adapted to communicate fluid pressure to said output member to move said output member in an opposite direction;

a first conduit means connecting said pump high pressure outlet to one of said motor port means;

a second conduit means connecting said pump low pressure inlet to the other of said motor port means;

remotely controlled means connected to said first conduit means for selectively reducing the pressure in said first conduit means to a lower predetermined value after said fluid motor output member moves a predetermined distance in a selected direction;

pressure responsive means for varying the fluid displacement of said variable displacement pump;

a second source of fluid pressure;

first means for communicating said second source of fluid pressure to said pressure responsive displacement varying means at a selected rate to control the rate of change in the increase in the displacement of said fluid pump to accelerate said motor output member;

second means alternately operable from said first means, said second means communicating said second source of fluid pressure to said pressure responsive displacement varying means at a second selected rate to control the rate of change in the decrease in the displacement of said fluid pump to decelerate said output member; and

means actuating said remotely controlled means simultaneously with actuation of said second means whereby the pressure of the fluid moving

said output member decreases to said lower predetermined value as said output member decelerates.

4. The multiple pressure fluid system defined in claim 3 wherein said fluid motor means comprises a main fluid cylinder having a piston reciprocably mounted therein and movable in response to the fluid pressure acting on the opposite sides of said piston, the effective pressure responsive areas on the opposite sides of said piston being equal; said fluid system further comprising valve means selectively connecting the inlet and outlet of said fluid pump to the opposite sides of said piston to direct fluid to said piston and exhaust fluid from the other side of said piston to move said piston.

5. The multiple pressure fluid system defined in claim 3 wherein said remotely controlled means comprises a remote control relief valve having an inlet connected to said first conduit means and an outlet connected to said second conduit means whereby said relief valve is operable to direct fluid from said first conduit means to said second conduit means.

6. The multiple pressure fluid system defined in claim 3 further comprising a directional control valve connected to said first and second conduit means for selectively connecting said first and second conduit means to said fluid motor first and second port means, said remotely controlled means comprising a remote control relief valve having its inlet connected to said first conduit means and its outlet connected to said second conduit means.

7. The multiple pressure fluid system defined in claim 3, further comprising a valve means, said first and second conduit means comprising a first fluid line and a second fluid line respectively communicating said pump high pressure outlet and low pressure inlet to said

valve means and a third fluid line and a fourth fluid line respectively communicating said first and second motor port means to said valve means, said valve means selectively connecting said first and second fluid lines to said third and fourth fluid lines such that the high pressure fluid in said first fluid line is directed selectively to one of said third or fourth fluid lines to move said output member in opposite directions, while fluid in the other of said third or fourth line is exhausted through said second fluid line, said remote controlled means comprising a first remote control relief valve having its inlet connected to said third fluid line and its outlet connected to said fourth fluid line, and a second remote control relief valve having its inlet connected to said fourth fluid line and its outlet connected to said third fluid line, whereby the pressure in whichever of said fluid lines carrying said high pressure fluid may be selectively reduced to a lower predetermined value after said movable output member is moved a predetermined distance.

8. The multiple pressure fluid system defined in claim 1, wherein said pressure relief valve is preset to open communication between its inlet and its outlet when the pressure in said first fluid line is at or above said lower predetermined value, said pilot valve means being a directional flow control valve movable between a first position closing fluid communication between said pressure relief valve inlet and said first fluid line and a second position opening communication between said pressure relief valve inlet and said first fluid line to reduce said high pressure fluid in said first fluid line to said lower predetermined value, said directional flow control valve being movable to said second position after said mechanical output is moved said predetermined distance.

[57] ABSTRACT

A fluid system having a variable displacement fluid pump connected in a closed loop circuit to a fluid cylinder having a piston and a pair of connecting rods extending from opposite sides of the piston externally of the fluid cylinder. A main directional control valve disposed in the closed circuit between the inlet and outlet of the fluid pump is adapted to selectively direct fluid to one side of the piston within the fluid cylinder, while exhausting fluid from the other side of the piston, to selectively move the piston within the fluid cylinder. The rate of movement of the piston in either direction of movement is controlled by the amount of fluid displaced by the fluid pump.

A second directional control valve is adapted to fluid FLUID from a second source of fluid to a pressure responsive displacement control mechanism to selectively vary the displacement of the fluid pump between a maximum and a minimum value. The rate of fluid flow to the pressure responsive displacement control mechanism is selectively varied to control the rate of displacement of the fluid pump and to thereby selectively control the rate of movement of the cylinder piston.

A remotely controlled pilot operated pressure relief valve, having an inlet connection in fluid communication with the outlet conduit of the fluid pump upstream from the main directional control valve and an outlet connection in fluid communication with the inlet conduit of the fluid pump between the fluid pump and the main directional control valve, is operable to reduce the normal operating pressure in the outlet conduit, and thus the operating pressure of the fluid in the main fluid cylinder, to a lower predetermined value when the pressure responsive displacement control mechanism is actuated to vary the displacement of the fluid pump toward a minimum value.
